BY *J. H. O'Creedy*,
ATTORNEY.

UNITED STATES PATENT OFFICE

LAWRENCE DAVIS, OF WALPOLE, MASSACHUSETTS

LABEL

Application filed November 17, 1931. Serial No. 575,538.

This invention relates to packages and to labels for use on packages.

It is frequently desirable to attach a letter to a package in order to ensure the consideration of the subject matter of the letter in connection with the goods contained in the package. While special boxes and containers are available for this purpose they are necessarily manufactured in certain definite sizes and consequently are not available in dimensions suitable for many purposes. In addition, they are relatively expensive and this fact also serves to limit their use.

The present invention aims to devise a label which can be used more universally in connection with the shipment of goods with a letter attached.

The nature of the invention will be readily understood from the following description when read in connection with the accompanying drawing, and the novel features will be particularly pointed out in the appended claims.

In the drawing,

Figure 1 is a perspective view showing a label embodying this invention and illustrating a step in the process of securing a letter to a package with this label;

Fig. 2 is a plan view of the completed package; and

Fig. 3 is a skeleton sectional view on the line 3—3, Fig. 2.

The label shown in the drawing at 2 may be made from any suitable sheet material such as tough paper or paper and cloth combined. Preferably the entire back or rear surface of the label is coated with a gum or some suitable adhesive, as indicated at 3, Fig. 1. The label includes a rectangular section 4 which, in this case, is outlined in the printing operation and which is adapted for securing a letter to the package. This section is slightly larger than an envelope of a standard size, and it is provided with an aperture or window 5 through which the address on the letter may be exposed. The label also includes designated spaces 6 and 7 for the letter postage and parcel post stamps, and a space 8 for the address of the sender.

According to the usual method of using

this label a letter, such as that shown at 10, is placed in a suitable position on the upper surface of the wrapper of the package 12, the gummed surface 3 of the label is then moistened to make the adhesive tacky, the label next is placed upon the letter with the window 5 properly centered with reference to the address on the letter, and the entire surface of the label is pressed against the letter and the wrapper, care being taken to see that the label is securely united to both of these members. Since the label completely surrounds the letter and is adhesively secured to the entire margin of the letter, it securely unites the letter to the wrapper. Proper stamps may be placed on the label, the return address inserted if necessary, although usually this will be printed on the labels preparatory to using them, and the package then is ready to be shipped.

Preferably the label is provided with a scored or dotted line 14, together with suitable printed directions 15 indicating the point at which the label should be cut to obtain access to the letter. This location of the line of cut should be borne in mind in placing the label on the package. The operation of positioning the letter and the label relatively to each other is facilitated by the rectangular outline printed on the label and bounding the section 4. It is sometimes desirable, also, to make the label with inclined cuts 16 leading approximately from the corners of the window toward the corners of the section 4 in order to provide four flaps surrounding the window. Some users find that this flap construction facilitates the application of the label to the package and the letter, and makes it easier to produce the desired adhesive union of the label to the letter and to the wrapper at points adjacent to the letter. This construction may or may not be used, as desired.

The invention thus provides a label which can be manufactured very economically, and can be used on packages of any size large enough to take the label. The invention therefore effects an economy in the preparation of shipment of a great variety of packaged goods. The address on the letter

becomes the address of the entire package so that confusion and mistakes in addresses are minimized.

It is contemplated that the section of the label removed to form the window 5 may be cut around three sides and scored on the fourth side so that it will be left attached to the other parts of the label, and that directions for using the label may be printed on 10 the flap so formed. This flap will be removed before or when the label is used so that the label as it finally goes on to the package will appear substantially as shown in Figs. 1 and 2. However, it forms a 15 convenient location for printing instructions which are desirable when the labels are to be sold to the general public or are to be distributed to the public in any other way. For example, it is contemplated that the mail 20 order houses may send such labels to their customers with a shipment of goods to facilitate the return of the goods to them if necessary for any reason.

Having thus described my invention, what 25 I desire to claim as new is:

1. An article of character described comprising a package, a label adhesively secured to said package, a letter held on said package by said label, the label surrounding the letter 30 and being adhesively united to both the margins of the letter and the adjacent surface of the package but having a window through which the address on the letter is exposed, whereby said address also serves as the address for the package.
2. An article of the character described comprising a package including a wrapper in which the packaged material is enclosed, a letter supported on the surface of said wrapper, and a label adhesively secured to the surface of the wrapper around said letter and also adhesively united to the margins of the letter, whereby it serves to hold said letter securely on the package, said label having a 45 window through which the address on the letter is exposed and being provided with means for indicating the line along which the label should be cut to permit the removal of the letter.
3. A label for securing a letter to a package, said label having its rear surface coated with gum and comprising a section shaped to fit over the marginal portions of a letter and to be adhesively secured thereto and to the adjacent portion of a package, said section having a window through which to expose the address on the letter, and being provided at one side of said window with means for indicating the line along which the label should 55 be cut to permit access to the letter, and said label having spaces on the face thereof for both the letter postage and parcel post stamps and for the address of the sender.
